AIR-COOLED EXHAUST MUFFLER WITH
FRUSTO-CONICAL BODY

Walton W. Cushman, Webb City, Mo.

Application January 26, 1948, Serial No. 4,221

4 Claims. (Cl. 181—43)

(Granted under the act of March 3, 1883, as
amended April 30, 1928; 370 O. G. 757)

1

The invention described herein, if patented, may be manufactured and used by or for the Government for governmental purposes without the payment to me of any royalty thereon.

The present invention relates to mufflers for the exhaust of internal combustion engines and has for its primary object to provide a muffler so designed as to eliminate the possibility of sparks or flames being emitted therefrom.

Another object of the invention resides in the provision of a spark and flame arresting muffler which is of relatively simple and inexpensive construction and yet which is highly effective in deadening the sounds emanating from the engine cylinders and in disposing of any sparks and flames prior to their reaching the rear end of the muffler.

Other objects and advantages of the invention will be apparent from the following description when taken in connection with the accompanying drawings, in which

Figure 1 is a side elevational view of the muffler, with parts broken away,

Figure 2 is a transverse sectional view taken on the line 2—2 of Figure 1, and

Figure 3 is a similar view taken on line 3—3 of Figure 1.

Basically, the invention comprises a hollow elongated body flared outwardly and rearwardly to permit an expansion of the exhaust gases as they leave the exhaust pipe and travel along the length of the muffler, in combination with means for rapidly diluting the exhaust gases with air to not only break down the sound waves but also to cool the gases to a temperature at which combustion will not take place and to a mixture ratio well outside the range of combustibility, i. e., somewhat above twenty (20) parts of air to one (1) part of gasoline.

In the present illustration of the invention the numeral 1 indicates the body of the muffler which is formed of any preferred metal and is of frusto-conical shape; the smaller end being secured to the rear end of an exhaust pipe 2.

The mounting for the muffler comprises a ring 3 secured to the smaller end of the muffler by a plurality of webs 4 so that the ring is concentrically arranged with respect to the muffler and is spaced inwardly of its walls. The muffler may be secured directly to the exhaust pipe 2, but it is preferred that a short tubular member 5 be connected to the inner wall of the ring 3, by welding or otherwise, and that the tubular member be clamped to the exhaust pipe by means of a clamping ring 6 and bolt 7. The tubular

member 5 is of course provided with one or more slits 8' to permit it to be contracted by the clamping ring 6 so as to firmly grip the exterior of the exhaust pipe. The inner end of the tube 5, that is, the end extending into the interior of the muffler is tapered as indicated by the numeral 8 for the purpose of speeding the flow of exhaust gases so as to increase the suction effect within the muffler as more fully set forth hereinafter.

The smaller end of the muffler body 1 is flared outwardly as indicated by the numeral 9 for the purpose of trapping a larger quantity of atmospheric air and directing it into the muffler, and the body of the muffler itself is provided with a plurality of annular series of struck-up cup-shaped tongues 10 associated with apertures 11. The tongues 10 are directed toward the smaller end of the muffler body and thus supplement the action of the flared portion 9 of the muffler in directing air into the interior of the muffler. It will be understood of course that while these tongues and apertures 10 and 11 are shown as uniformly arranged in annular series they may be arranged in any preferred manner so long as they cover a major portion of the wall of the muffler and extend throughout its length.

In the operation of the muffler the current of exhaust gases passing through the tube 5 and narrowed end 8 provide a suction or aspirating effect so as to draw air in through the flared end 9 of the muffler body to supplement the action of the forward movement of the vehicle and the muffler which is attached thereto. This high volume of air entering the muffler tends to dilute the gases and break up the sound waves and this action is supplemented by the many currents of air entering the muffler throughout its length by reason of the inclined tongues 10 and the apertures 11 associated therewith. Moreover, the flared construction of the muffler contributes to this same result by allowing the further expansion of the gases as they travel rearwardly. By reason of these several cooperating actions upon the exhaust gases the sound caused by the explosions in the cylinders are materially reduced and the possibility of sparks or flames passing outwardly from the rear end of the muffler is eliminated due to the fact that the large amount of air entering the muffler will dilute and cool the gases beyond the point at which combustion will be supported.

While the muffler has been described in some detail the invention is not so limited in scope, and it is therefore intended that the present dis-

closure be considered as illustrative of the invention rather than in a limiting sense.

I claim:

1. A muffler comprising an interiorly unobstructed, hollow, open-ended frusto-conical body provided with an outwardly-flared portion on its smaller end, means for securing the smaller end of the body to the end of the exhaust pipe of an engine in axial alignment therewith and with the wall of the smaller end spaced radically outward of the wall of the exhaust pipe, the wall of said body provided with a plurality of apertures, and means for directing air inwardly through said apertures.

2. A muffler comprising an interiorly unobstructed, hollow, open-ended frusto-conical body having its exterior wall exposed to the atmosphere and provided with an outwardly-flared portion on its smaller end, means for securing the smaller end of the body to the end of the exhaust pipe of an engine in axial alignment therewith and with the wall of the smaller end spaced radically outward of the wall of the exhaust pipe, and a plurality of tongues struck-up from said body and extending toward the smaller end thereof.

3. A muffler comprising an interiorly unobstructed, hollow, open-ended frusto-conical body having its exterior wall exposed to the atmosphere and provided with an outwardly-flared portion on its smaller end, the wall of said body provided with a plurality of apertures, means for directing air through said apertures, and an open-

ended tube of relatively small diameter secured in the smaller end of the frusto-conical body and having its inner end tapered.

4. A muffler comprising an open-ended, hollow, frusto-conical body having its exterior wall exposed to the atmosphere and provided with an outwardly-flared portion at its smaller end, means for securing the smaller end of the body to the exhaust pipe of an engine in axial alignment with the exhaust pipe, the wall of the body being radically spaced from the exhaust pipe, said muffler body being provided with a plurality of apertures, and means for directing air through said apertures comprising cup-shaped tongues struck-up from the body and extending toward the smaller end thereof.
